UNITED STATES PATENT OFFICE.

ADLAIS SNEVA, OF DIVIDE COUNTY, NORTH DAKOTA, ASSIGNOR OF ONE-FOURTH TO
E. A. SNEVA, OF COUNTY OF DIVIDE, NORTH DAKOTA.

SHOE-CLOSURE.

1,294,965.

Specification of Letters Patent.

Patented Feb. 18, 1919.

Application filed April 20, 1917. Serial No. 163,425.

To all whom it may concern:

Be it known that I, ADLAIS SNEVA, a citizen of the United States, residing in the county of Divide and State of North Dakota, have 5 invented certain new and useful Improvements in Shoe-Closures; and I do hereby declare the following to be a full, clear, and exact description of the invention, such as will enable others skilled in the art to which 10 it appertains to make and use the same.

This invention relates to improvements in shoe closures.

The object of this invention is the provision of a shoe closure which will obviate the 15 necessity of the use of lacings and buttons, and by means of which the open front side of the shoe may be effectively closed against the admission of water, snow or the like.

A still further object of this invention is 20 the provision of means whereby the upper may be brought into and held in snug and comfortable engagement with the ankles.

A still further object of this invention is 25 the provision of a shoe closure which will materially add to the appearance of the shoe and also one that will be easily and quickly secured about the ankle and upon the foot of the user.

A still further object of this invention is 30 the provision of a shoe closure of this character which will be simple, practical and comparatively inexpensive in construction and one that can be manufactured and sold at a low cost.

35 With these and other objects in view the invention consists in the novel combination and arrangement of parts hereinafter more fully described and set forth in the claims hereto appended.

40 In the drawing:

Figure 1 is a view in side elevation of a shoe constructed in accordance with my invention,

45 Fig. 2 is a similar view in side elevation illustrating the opposite side of the shoe,

Fig. 3 is a front elevation illustrating the shoe in open position, and

50 Fig. 4 is a plan view of the buckle retaining strap which is secured to one side of the shoe.

Like numerals of reference designate corresponding parts in all the figures of the drawings.

55 Referring more particularly to the drawings the numeral 1 designates the vamp and

2 the upper of the shoe constructed in accordance with my invention, the upper comprising the sides 3 and 4.

The closure comprises the inner member 5 and outer member 6 and they are secured to 60 the sides 3 and 4 of the upper 2 which will be hereinafter more fully described.

The inner closure 5 is substantially triangular and is secured by one side edge to the forward free edge of the side of the 65 upper 2 as at 7 by suitable stitches 8 the apex being secured to the vamp as at 9 and the inner closure is adapted to be forced inwardly against and about the ankle and snugly conformed thereto.

The outer closure 6 comprises a substantially V-shaped portion which is secured by its base to the edge of the side 4 of the upper 2 by suitable stitches 9' and it is secured to the vamp as at 10 and the apex 11 of the 75 outer closure 6 is extended to provide the tongue 12 which is provided with spaced openings 13.

A buckle retaining strap 14 has a tapered medial portion 15 and is looped back upon 80 itself at its medial portion on the line 16 and the medial portion 15 is provided centrally with an opening 17 adapted to receive therethrough the tongue of the buckle 12', thus the buckle will be secured between the 85 bent back portions of the securing strap 14 the edges of the strap 14 being stitched together as at 18 and the same line of stitches also securing it to the vamp of the shoe as at 19.

The buckle retaining strap 14 is secured to one side of the shoe with its medial portion inclining upwardly and rearwardly thus positioning the buckle in diagonal plane from the rear medial portion of the upper, 95 thus it may be seen that when the outer closure strap is carried around the shoe it will engage the rear portion of the upper adjacent the upper edge thereof and extend downwardly and incline in the direction of 100 the lower portion of the shoe and in the direction and plane of the buckle so that it may be securely fastened in the buckle and the tongue of the buckle passing through the openings 13 in the strap 12 of the outer 105 closure 6 thus effectively and snugly securing the upper about the ankle of the user.

To give the outer member 6 a curvature conforming to the configuration of the ankle, this member is substantially V-shaped 110

and has a substantially curved base which when secured to the forward edge of the side 4 of the upper it will readily conform to the configuration of the ankle when fastened thereabout thus permitting the closure to effectively and snugly fit the ankle of the user.

In operation:

The shoe is placed upon the foot of the wearer, the inner flap is folded across the forward portion of the ankle around the side thereof the closure 6 is drawn around in opposite direction about the ankle and completely incloses the inner closure 5, the strap 12 is extended to the opposite side of the shoe to fasten in the buckle as illustrated in Fig. 1 and the shoe is effectively secured to the foot of the user.

It can be readily seen by the securing of the strap 12 in the buckle that the open front side of the shoe is sealed and prevent water, snow or the like from getting into the shoe.

What is claimed is:

1. A shoe having the sides of its upper provided with overlapping inner and outer closure members, and a fastening means consisting of a tongue and a tongue engaging device carried respectively by the outer closure member and shoe side which supports the same.

Copies of this patent may be obtained for five cents each, by addressing the "Commissioner of Patents, Washington, D. C."

2. A shoe having the sides of its upper provided with overlapping inner and outer closure members of which the latter carries a tongue to extend around the rear of the shoe upper, and a tongue engaging device carried by the shoe side which supports said outer closure member. 35

3. A shoe having right and left upper-sides provided with extensions forming 40 overlapping unconnected inner and outer closure members, and complementary fastening elements carried by one of said upper-sides, and including an ankle embracing tongue. 45

4. A shoe having its upper composed of right and left side members which are unconnected at their front edges, closure members connected respectively with said side members to overlap on a median line between the same, and complementary fastening elements, one of which consists of a tongue, carried respectively by the exterior closure member and the side member to which it is connected. 50

In testimony whereof I affix my signature in presence of two witnesses.

ADLAI SNEVA.
